UNITED STATES PATENT OFFICE.

GEORGE F. KUETT, OF PATERSON, NEW JERSEY, ASSIGNOR TO THE AMERICAN AUTOMATIC LOOM COMPANY, OF NEW JERSEY.

NEEDLE-LOOM.

SPECIFICATION forming part of Letters Patent No. 643,902, dated February 20, 1900.

Application filed July 12, 1899. Serial No. 723,543. (No model.)

To all whom it may concern:

Be it known that I, GEORGE F. KUETT, a citizen of the United States, residing in Paterson, in the county of Passaic and State of New Jersey, have invented certain new and useful Improvements in Needle-Looms; and I do hereby declare the following to be a full, clear, and exact description of the invention, such as will enable others skilled in the art to which it appertains to make and use the same, reference being had to the accompanying drawings, and to letters and numerals of reference marked thereon, which form a part of this specification.

This invention relates to looms; and it has reference particularly to a loom in which needles are employed for controlling the weft or filler.

The object of the invention is to provide a loom of the character above particularly referred to in which the most efficient coaction of the needles will be effected and in which the construction and arrangement of the parts controlling said needles will be most suitable in the way of simplicity, durability, and efficiency of operation for the performance of their several functions.

The invention consists in the improved needle-loom and in the combination and arrangement of its various parts, substantially as will be hereinafter pointed out and finally embodied in the clauses of the claim.

The invention is fully illustrated in the accompanying drawings, wherein corresponding letters and numerals of reference indicate like parts in the several figures, and wherein—

Figure 1 is an end view of the lower portion of a loom constructed after the principles of my invention. Fig. 2 is a longitudinal sectional view of a portion of my improved loom, showing in rear elevation the batten, the needles for controlling the weft or filler, and portions of the operating mechanism for the respective sets of needles. Fig. 3 is a top plan view of what is shown in Fig. 2. Figs. 4, 5, and 6 are enlarged detail views of certain parts of the loom, Fig. 4 being a sectional view showing the relative arrangement of the batten, one of the reeds, and the needles, and Figs. 5 and 6 being, respectively, a top plan view and a side view, partially in

section, of a pair of one of the sets of needles and their supporting or carrying means, the sections in Fig. 6 being taken substantially centrally of corresponding parts in Fig. 5. Fig. 7 illustrates a portion of the mechanism connecting the batten and the main drive-shaft and adapted to reciprocate the former. Fig. 8 is an enlarged view of a certain tension device for controlling the weft or filler; and Figs. 9 and 10 are enlarged detail views showing a certain modification of a portion of my invention, Fig. 9 being a plan view and Fig. 10 being a view in side elevation thereof.

a in the accompanying drawings designates one of the side frames of the loom, and *b* and *c* designate beams connecting said side frames, the former being the breast-beam and the latter supporting a series of parting-bars *d*, arranged in any suitable frame, through which the warp-threads *e* extend, said warp-threads being maintained under the proper tension by weights *f* and controlled by suitably-operated harness *g*.

h designates lay-swords which may be fulcrumed in any suitable manner at their upper ends in the upper part of the frame of the loom and which carry at their lower ends the batten *i*.

j designates the main drive-shaft of the loom, said shaft being suitably journaled in the side frames and carrying a fly-wheel *k*. Projecting downwardly from and secured to the batten is an inverted-T-shaped bracket *l*, the horizontal portion of which is provided with a slot *m*, in which a bolt *n* is adjustably arranged, said bolt constituting a pivotal connection with said bracket for one end of a pitman *o*, the other end of which is connected by a link *p* with the fly-wheel *k*. It should be remarked that the pitman *o* is guided for a horizontal or substantially-horizontal movement or longitudinal reciprocation by a lever *q*, pivotally connected to said pitman near its point of connection with the link and fulcrumed in the frame.

It is my object to effect a pause in the batten in its retracted position of more or less duration, and if the link be of such length that its point of pivotal connection with the pitman *o* will be brought into proximity to the shaft *j* during each rotation of the latter

this will be most effectually accomplished for all practical purposes, for then the oscillating end of the link and the point on the wheel *k* where it has pivotal connection will travel 5 in arcs of circles that extend for a more or less distance in practical coincidence, as indicated, for instance, by the portion *r s* of the circle shown in dotted lines in Fig. 7. The purpose of effecting this temporary in- 10 termittent stopping of the batten in its retracted position will be hereinafter set forth. It may be remarked that the foregoing mechanism, which provides connection between the batten and the fly-wheel, should by preference 15 be duplicated, one such mechanism being provided at each end of the loom, so as to effect a true movement of the batten.

The batten is provided in its upper portion with a longitudinal groove *t* disposed near its 20 rear edge, and in said groove is arranged side by side for longitudinal movement a pair of bars *u v*. Each bar *u v* is surmounted by a metallic strip *w* or series of strips preferably secured thereto by screws and provided with 25 a series of openings *x*. Each opening is covered by a plate *y*, having longitudinal slots *z* therein, each slot being penetrated by a screw *l*, which is secured in the strip. Each plate is thus longitudinally adjustable upon 30 the strip.

2 designates a post which is screwed into the plate, being maintained in any desired position therein by a binding-nut 3. The head *t* of each post is penetrated by trans- 35 verse intersecting openings 5, either of which is adapted to receive the rear end of a needle 6, maintained in position by a set-screw 7. Each needle is preferably L-shaped, its portion 40 8 being disposed longitudinally with reference to the batten and provided near each of its ends with an opening or eye 9.

The needles 6 are disposed in pairs, the members of each pair being movable from opposite sides of each reed and in opposite 45 directions, as best shown in Figs. 2 and 3, said needles being disposed out of horizontal alignment with each other, preferably by providing a slightly higher post 2 for the one than for the other.

50 Each reed is sustained back of the batten, and consequently back of the needles, above described. The needles are formed substantially L-shaped, so that they may be brought into the most effective proximity to the reed 55 by adjusting them by means of the set-screw 7. Each reed is mounted in a pair of lathe-plates 10, having coacting vertical clamps 11 adjustably secured thereto by means of screws 12, set in horizontal slots formed in each 60 lathe-plate. The reed preferably rests upon pins 13, projecting from each lathe-plate. Each of the lathe-plates is secured to the back of the batten by screws 14, said lathe-plate being spaced from the batten by blocks 65 15, which the screws penetrate and thereby hold in place.

The bars *u v* are adapted to be recipro-

cated, so as to move the needles which they carry, by means of bell-crank levers 16, fulcrumed in bearing-plates 17, suitably secured to and projecting upwardly from the batten. Said bars are connected with the levers by means of rods 18, one end of each of which is pivoted in one arm 18^a of a corresponding lever, and the other end of each of which is pivoted in a block 19, secured upon the top of the bar. It should be remarked that the batten is extended at one end, so as to sustain the lever 16. It should also be remarked that a roller-bearing projection 20 extends upwardly from one side of the batten and over the top of the same and each bar *u v* in order to maintain the latter in its position in the groove *t*.

There is a vertically-movable frame disposed back of the batten and of the series of lathe-plates and consisting of a pair of horizontal rails 21 22, connected at their ends by metallic plates 23 and intermediately of said plates by braces 24. Vertical guides 25, in 90 the grooves 26 of which the plates 23 are movable, are provided, being secured to the back of the batten and adapted to insure a true reciprocating movement of the frame. It should be remarked that principally in order to strengthen the rails 21 22, which may be of wood, reinforcing metallic strips 27 are provided.

The other set of needles employed in my loom are designated by the reference character 28. These needles are movable vertically or, in other words, transversely with reference to the direction of movement of the other needles, and each of them is perfectly straight and has its upper end sharpened. Each needle penetrates a block 29, in which it is adjustably maintained by means of a set-screw 30, each block being pivotally mounted in a lug 31, projecting from a clamp 32, adapted to receive the upper rail 21 of the vertically-movable frame, and to be secured thereto by means of a set-screw 33. Each needle is therefore oscillatory—that is to say, they are susceptible of a certain yielding motion, as hereinafter described in setting forth the operation of the loom. From the upper end of said clamp and over the lug 31 projects an arm 34, having a slot therein through which the needle extends and in which it is movable about the pivotal point of the block 29. It should 100 be remarked that the needle is movable vertically between the planes of the rear face of the batten and the front face of the reed and directly in front of the line of movement of the portions 8 of the needles 6. The action 105 of gravitation tends to maintain it in the position shown in Fig. 4; but, if desired, a spring 109, shown in dotted lines in said figure as connecting the lower end of the needle and the vertically-movable frame, may be employed.

On the shaft *j* and inside of the side frame *a* of the loom which is adjacent to the extended portion of the batten is mounted a gear 35, that is adapted to transmit rotary move-

ment through a suitably-journalled pinion 36 to a gear 37, also journalled inside of the side frame *a* on a shaft 38. The shaft 38 is journalled in the side frame *a*, above referred to, and also in a standard 39, disposed outside of said side frame, and between said standard and the side frame there is a pair of reversely-disposed cams 40, each having a pear-shaped cam-slot 41 therein, in which works a roller 42, mounted upon the upper end of an arm 43, that extends upwardly from each of a pair of levers 44, which are fulcrumed upon a bolt 45, arranged for vertical adjustment in the rear portion of the side frame. The free end of each of the levers 44 is connected to the free arm of one of the bell-crank levers 16 by means of an adjustable pitman 46. 47 is a vertical upright having slots 48 therein, through which the levers 44 project, said upright being thus adapted as a guide for the levers.

49 is a revolute shaft journalled at each of its ends in the side frames *a* and supported, if desired, by any desirable means intermediate of said side frames. Upon said shaft 49 is keyed a series of eccentrics 50, each embraced by an eccentric-strap 51, an open projection 52 of which is penetrated by the lower threaded end of a pitman 53, adjustably secured thereto by means of nuts 54, the upper end of each pitman being trunnioned in lugs 55, projecting from the lower rail of the vertically-movable frame. Said shaft 49 carries a gear 56, eccentrically mounted thereon and meshing with an elliptical gear 57, carrying a pinion 58, to which a rotary movement is imparted from a gear 59, mounted on the shaft *j*, through an intermediate pinion. The elliptical gear 57, together with the pinion it carries and also the intermediate pinion, may be journalled in some intermediate portion of the loom-frame or in special supports provided for the purpose.

The weft thread or filler 60 extends from the spools or bobbins 61, upon which it is wound, to the eyes of the needles 6 through an intermediate tension device 62. Each bobbin and tension device is preferably mounted upon an individual suitably-supported plate 63, the former resting upon a block 64, mounted on said plate. Upon the plate and over the bobbin stands an arch-shaped frame 65, carrying levers 66 67, by preference formed of bent wire, said levers being fulcrumed midway between their ends upon opposite sides of the arch, their lower ends being drawn toward each other by crossed springs 68, connecting them with the plate. The lower portion 69 of the lever 67 is curved inwardly toward the bobbin, and the lower portion of the lever 66, which is somewhat longer than that of the lever 67, is bent back upon itself, the rebent portion 70 being also curved inwardly, but approaching more nearly to the bobbin than the curved portion of the lever 67. Upon the bobbin and journalled upon the spindle 71 therefor is a flier consisting of a block 72,

having delicate and elastic diametrical upwardly and downwardly extending wire arms 73, provided with eyelets 74 at their free ends, through which the thread extends from the bobbin to an eyelet 75, secured at the top of the arch-shaped frame, and thence through eyelets 76 of the levers 67 and 66.

The device above described not only acts to maintain the proper tension upon the thread, but also acts to immediately stop the feed thereof as soon as the pull upon the thread is relaxed. If there is a sudden pull or jerk upon the thread, it will be apparent that the lever 66 will move before and to a somewhat-greater extent than the lever 67, and therefore it is to prevent the downwardly-extending arm 73 of the flier from moving past the inwardly-projecting portion 70 of the lever 66 without engaging the same at this moment that said curved portion extends more nearly to the bobbin than the curved portion 69 of the other lever. The device should be constructed, therefore, with the object of effecting an engagement between the downwardly-extending arm 73 and each of the inwardly-projecting portions of the lever in each revolution of the flier.

The woven goods 77 extends over a bar 78, supported upon the breast-beam *b* to the take-up roll 79, said take-up roll carrying a pinion 80, adapted to be rotated through an intermediate pinion 81 by a gear 82, said last-named gear being in mesh with a pinion 83, carrying a ratchet-wheel 84, with the teeth of which a pawl 85, that is carried by a lever 86, engages, said lever being movable concentrically with the gear 83 under actuation of the batten *i*, to which it is connected by a cord 87.

In describing the operation of the machine it is to be first remarked that the main drive-shaft *j* rotates in the direction of the arrow *R* in Figs. 1 and 7, and it is assumed that the starting position of the several parts of the loom is that shown in Fig. 1. As the shaft *j* rotates it draws the batten back through the link *p*, the pitman *o*, and the bracket *l* until the point of pivotal connection of the link *p* with the wheel *k* enters the arc *r s* of the circle of rotation of said pivotal point, whereupon, as before stated, the batten comes to a standstill. Meanwhile through the system of intermeshing gears 35, 36, and 37 the shaft 38 is rotated, the arrangement of the gearing being such that said shaft revolves in the same direction as the shaft *j* and at one-half the speed thereof. Thereupon while the batten is at a standstill, the shed being at this time opened by the shedding mechanism, one of the levers 44 will be depressed by virtue of the engagement of its roller-bearing arm 43 with that portion of the slot 41 of the cam 40 which is farthest from the center thereof. The depression of the lever 44 effects, through the pitman 46, a movement of the corresponding bell-crank lever 16 about its fulcrum, the motion of said lever being transmitted through the rod 18 and the block 19 to the bar

u, carrying through the several sheds the needles of the set of needles 6 which are mounted on said bar. Also while the batten is at rest in its retracted position the shaft j, through 5 the gear 35, the pinion 59, the elliptical gear 57, and the eccentrically-arranged gear 56, effects a rotation of the shaft 49, carrying said gear 56 and the eccentrics 50. The rotation of the shaft 49 will of course be in the direction of the arrow T in Fig. 1. The rotation of the eccentrics 50 on said shaft 49 effects a lifting, through the pitman 53, of the vertically-movable frame carrying the needles 28. It should be remarked at this point that said 10 needles 28 are disposed in proximity to each side edge of each reed and that they are adapted to engage the thread which the needles 6 carry through the warp in order to form and maintain loops in the filler. As the needles 28 are carried upwardly by their frame, therefore, those of them which are adjacent to the points of the needles 6 that have just passed through the shed engage the thread or filler carried by said needles 6 and form 15 loops. Thereupon the pear-shaped cam having moved far enough and the lever 44 being therefore raised and the bell-crank lever 16 being consequently actuated, the needles 6 will be withdrawn from their positions in the 20 sheds. By this time the shaft j will have rotated far enough so that the batten will begin to be again forced forward in order to beat up the loops of the weft that are being maintained by the needles 28. During the forward 25 movement of the batten the needles 28 begin to descend; but they engage and maintain the loops in the weft until just before the reed carried by the batten reaches the limit of its forward movement, or, in other words, completes 30 the beating up of the weft, whereupon they slip out of the loops and are quickly retracted at or slightly before the instant of beating up. Owing to the relative disposition that has meantime been assumed by the members of 35 the gearing which connects the shaft j and the frame carrying the loopers and to the fact that since the elliptical gear 57 and the eccentrically-arranged gear 56 intermittently engage each other at points on the one which 40 are remote from its center of rotation, while the corresponding points on the other are in proximity to its center of rotation, the speed of the eccentrically-arranged gear is alternately fast and slow. It will be apparent, in 45 view of what has just been said, therefore, that the needles 28 are pivotally mounted because they should be free to give way at the time just before the weft is beaten up and while they are still in engagement with the loops. 50 The next revolution of the shaft j will effect a repetition of the operation as just described, the only difference being that at this time the needles 6, mounted on the bar v, will be moved, as will be obvious. 55 The operation of the tension device 62 has been already described. When it is stated that the movements of the batten effect.

through the flexible connection 87, the movements of the lever 86, the operation of the take-up mechanism will be apparent. 70

In the modification shown in Figs. 9 and 10 the needles which form the loops instead of moving vertically are adapted to move horizontally. The frame 88, which carries said needles, is exactly similar to the corresponding 75 or vertically-movable frame already described, the guides 89 therefor being secured to the under side of the breast-beam b. The needles 90 are adjustably mounted in blocks 91, pivotally secured to clamps 92, mounted 80 on one of the bars 93 of the frame 88, all in the same manner as in the corresponding construction hereinbefore described. Said needles are bent so as to extend rearwardly from their point of pivotal support, then upwardly 85 approximately parallel with the rear face of the breast-beam, and then rearwardly again substantially in the plane of the other needles 6. Said needles 90 are normally maintained in a horizontal position by means of a horizontal 90 rod 94, mounted at each end in a link 95, pivotally suspended from the frame 88, and the ends of said needles which form the loops are adapted to fall when their rear ends are tripped by a detent 96, projecting from the breast-beam and adapted to engage the pivotally-suspended bar 94. The frame 88, carrying said 95 needles, is reciprocated by means of eccentrics 97, mounted on a shaft 98, that is journaled in bearing-blocks 99, projecting from portions 100 of the loom-frame, said eccentrics carrying straps 100, to which are adjustably connected pitmen 101, having pivotal connection with lugs 102, projecting downwardly from the frame 88. The shaft 98 carries a sprocket 105 103, which is eccentrically mounted thereon and the teeth of which engage a sprocket-chain 104, passing over an elliptical sprocket 105, mounted on the shaft j. It should be remarked that one revolution of the elliptical 110 sprocket 105 is adapted to effect two revolutions of the sprocket 103. In the operation 115 of this modified portion of the mechanism of my improved loom as the needles 6, mounted on one of the rods u, (v,) carry the filler or weft through the sheds the needles 90 are advanced, this being effected by the movement which is imparted to the frame carrying them by the rotation of the eccentrics 97 that is imparted to said eccentrics from the shaft j 120 through the chain-and-sprocket connection. Said needles, coacting with the retracting needles 6, produce loops in the weft or filler, and as they reach the limit of their movement the rod 94 is tripped, permitting them to fall, 125 so that the loops are maintained taut to a more or less extent, and therefore the possibility of their being slipped past the ends of the needles 90 uncaught thereby is obviated. The loops being formed and the needles 6 having 130 retracted out of the sheds, the batten moves forward to beat up the weft, and just before the beating up is effected the frame carrying the needles 90 is quickly retracted,

the forward ends of said needles being lifted to the horizontal position, so that the rod 94 can be reset to maintain them in that position by another rod 106, carried by arms 107, 5 projecting from the breast-beam *b*. Each needle 90 may have a slight deflection 108 in it, so as to insure its being lifted high enough so that the rod 94 can be slipped in position. The operation above described is of course 10 repeated, so that the needles 90 may coact with the needles 6, mounted upon the other bar *v* (*u*).

I have hereinbefore remarked that each of the needles 6 has two eyes. This provision 15 is made so that the needle can act as a take-up of any looseness that may occur in the filler or weft. By passing the weft or filler through two eyes in the needle the latter can exert a tension upon the thread, and when it 20 retracts after the coacting needle enters the loop the superfluous portion of the loop that must necessarily exist in order that said coacting needle can enter the loop will be taken up. If there were only one eye in the needle, 25 the thread might freely slip through it, and the superfluous portion of the loop would not be taken up.

When in the claims I use the expressions "loopers" and "filler-carriers," it will of 30 course be understood that reference is made to the needles 28 (or 90) and 6, respectively.

Having thus fully described my invention, what I claim as new, and desire to secure by Letters Patent, is—

35 1. In a loom, the combination, with warp-controlling mechanism and a batten having a groove or grooves in its upper surface, of reciprocating bars seated in said groove or grooves, filler-carriers mounted on said bars, 40 loopers adapted to reciprocate transversely of said filler-carriers, levers fulcrumed on said batten and operatively connected to said bars, and means for vibrating said levers and reciprocating the loopers, said means being operative independently of the action of said batten, substantially as described.

2. In a loom, the combination, with warp-controlling mechanism and a batten, of reciprocating bars mounted on said batten, filler-carriers mounted on said bars, a suitably-guided frame carried by and movable transversely with reference to the batten, loopers carried by said frame and adapted to coact with the filler-carriers, levers mounted on said batten, rods pivotally connecting said bars and said levers, and means for vibrating said levers and reciprocating said frame, said means being operative independently of the action of the batten, substantially as described.

3. In a loom, the combination, with warp-controlling mechanism and a batten having a groove in its upper surface, of reciprocating bars seated side by side in said groove, 65 filler-carriers adjustably mounted on said bars, a vertically-movable frame carried by and movable transversely with reference to

the batten, guides for said frame carried by said batten, loopers carried by said frame, yieldingly mounted therein and adapted to coact with the filler-carriers, levers mounted on said batten, rods pivotally connecting said bars and said levers, and means for vibrating said levers and reciprocating said frame, substantially as described. 75

4. In a loom, the combination, with warp-controlling mechanism and a batten and with the drive-shaft, of reciprocating bars carried by said batten, filler-carriers mounted on said bars, levers fulcrumed on said batten and operatively connected to said bars, a vertically-movable and suitably-guided frame carried by said batten, loopers carried by said frame, yieldingly mounted therein and adapted to coact with said filler-carriers, suitably-journaled eccentrics operatively connected to said frame, suitably-fulcrumed levers operatively connected to said frame, suitably-fulcrumed levers operatively connected to said first-named levers, operative connecting means 90 between said drive-shaft and said eccentrics and between said drive-shaft and the last-named levers, and means for reciprocating the batten, substantially as described. 85

5. In a loom, the combination, with warp-controlling mechanism including a batten and with the drive-shaft, of reciprocating bars carried by said batten, filler-carriers mounted on said bars, levers fulcrumed on said batten and operatively connected to said bars, a vertically-movable and suitably-guided frame adapted to reciprocate transversely of said batten, loopers carried by said frame and adapted to coact with said filler-carriers, another and suitably-journaled shaft, eccentrics 105 and an eccentrically-mounted gear carried on said last-named shaft, operative connection between said eccentrics and the frame, a suitably-journaled elliptical gear engaging said eccentrically-arranged gear and operatively connected to the drive-shaft, suitably-journaled cams, gearing connecting said cams and the drive-shaft, levers operatively engaging said cams, pitmen connecting said levers and said first-named levers, and operative connecting means between said batten and the drive-shaft, substantially as described. 115

6. In a loom, the combination, with the batten and with reciprocating filler-carriers, of a vertically-movable frame, guides for said frame carried by said batten, clamps adjustably mounted on said frame, and loopers yieldingly carried by said clamps and adapted to coact with said filler-carriers, substantially as described. 125

7. In a loom, the combination, with the batten and with reciprocating filler-carriers, of a vertically-movable frame, guides for said frame-projecting downwardly from said batten, clamps adjustably mounted on said frame, oscillating blocks supported by said clamps, and loopers carried by said blocks and adapted to coact with said filler-carriers, substantially as described. 130

8. In a loom, the combination, with the batten and with reciprocating filler-carriers, of a vertically-movable frame, guides for said frame projecting downwardly from said batten, clamps adjustably mounted on said frame, oscillating blocks supported by said clamps, and loopers carried by said blocks and adapted to coact with said filler-carriers, each looper being disposed eccentrically of the pivotal axis of its block, substantially as described. 70
9. In a loom, the combination, with the batten and with reciprocating filler-carriers, of a vertically-movable frame, guides for said frame projecting downwardly from said batten, clamps adjustably mounted on said frame and provided with slotted projections at their upper ends, blocks pivotally connected to said clamps beneath the projections thereof, and loopers adjustably mounted in said blocks, penetrating said slotted projections and adapted to coact with said filler-carriers, substantially as described. 75
10. In a loom, the combination, with a batten having a longitudinal slot therein, of reciprocating bars arranged in said slot, strips secured upon said bars and having openings, slotted plates arranged on said bars over the openings therein, screws projecting into the strips and penetrating the slots of said plates, posts adjustably mounted on said plates over said openings and provided with adjusting-nuts, and needles penetrating and adjustably mounted on said posts, substantially as described. 80
11. In a thread-controlling device, the combination, with a spool or bobbin, of a pair of suitably-disposed coacting levers, a flier revolvably arranged in the axial line of said spool or bobbin and including an elastic arm provided with an eccentrically-disposed eyelet, said levers having eyelets at the ends thereof adjacent the flier, and said flier-arm being adapted to engage the other ends of said levers, and springs tending to separate the eyelet ends of said levers, substantially as described. 85
12. The combination, of a pair of suitably-fulcrumed spring-controlled coacting levers, a spool or bobbin disposed between the same, and a flier revolvably mounted above said spool or bobbin, and including an upwardly-extending arm and a downwardly-extending arm, the former carrying an axially-disposed eyelet and the latter carrying an eccentrically-disposed eyelet and the upper arms of the levers being also provided with eyelets, the lower arms of said levers being adapted to be engaged by the downwardly-extending arm of the flier, substantially as described. 90
13. The combination with an arch-shaped frame and a spool or bobbin arranged within the same, of a pair of coacting levers fulcrumed in said frame on opposite sides of said spool or bobbin, a flier revolvably mounted upon said spool or bobbin and comprising up- 95
- wardly and downwardly extending arms, and an axially-disposed eyelet carried by said first-named arm and an eccentrically-disposed eyelet carried by the other arm, said levers having eyelets at the ends thereof adjacent the flier and being adapted to be engaged by the downwardly-extending arm at the other of their ends, and springs tending to separate the eyelet ends of said levers, substantially as described. 100
14. The combination, with an arch-shaped frame and a spool or bobbin arranged therein, of a pair of levers fulcrumed in said frame on opposite sides of said spool or bobbin, a flier revolvably mounted upon said spool or bobbin and comprising upwardly and downwardly extending flexible arms, and an axially-disposed eyelet carried by said first-named arm and an eccentrically-disposed eyelet carried by the other arm, said levers having eyelets at the ends thereof adjacent the flier and having their other ends bent inwardly, the one more than the other, and adapted to engage said downwardly-extending arm, springs tending to separate the eyelet ends of said levers, and a stationary eyelet carried by said frame above said flier, substantially as described. 105
15. In a loom, the combination with the frame including a breast-beam and with shedding mechanism including the batten, of a horizontally - reciprocating frame, guiding means carried by said breast-beam and sustaining said reciprocating frame, filler-carriers movable longitudinally of said batten, means for actuating said reciprocating frame, loopers pivotally supported in said reciprocating frame and adapted to coact with said filler-carriers, a movable device engaging said loopers, and a detent adapted to trip said device to disengage the loopers therefrom, substantially as described. 110
16. In a loom, the combination, with warp-controlling mechanism, and a batten, of reciprocating bars mounted on said batten, filler-carriers mounted on said bars, loopers adapted to reciprocate transversely of said filler-carriers, levers fulcrumed on said batten, and operatively connected to said bars, a drive-shaft journaled in said frame, operative connecting means between said drive-shaft and said levers, operative connecting means between said drive-shaft and said loopers, a longitudinally-reciprocating pitman operatively connected to said batten, means for guiding said pitman, and a link pivotally connected at one of its ends to said pitman and having eccentric connection with said shaft at the other of its ends, substantially as described. 115

In testimony that I claim the foregoing I have hereunto set my hand this 10th day of July, 1899.

GEORGE F. KUETT.
